US00D534505S

(12) **United States Design Patent** (10) **Patent No.:** **US D534,505 S**
Kamada (45) **Date of Patent:** **** Jan. 2, 2007**

(54) **LIGHT EMITTING DIODE**(75) Inventor: **Kazuhiko Kamada**, Tokushima-ken (JP)

4,127,792 A 11/1978 Nakata
 5,226,053 A 7/1993 Cho et al.
 5,534,718 A 7/1996 Chang
 RE36,614 E 3/2000 Lumbard et al.

(73) Assignee: **Nichia Corporation**, Anan (JP)

(Continued)

(***) Term: **14 Years**
